UNITED STATES PATENT OFFICE.

GEORGE M. ROUSE, OF WESTMORELAND, NEW YORK, ASSIGNOR, BY DIRECT AND MESNE ASSIGNMENTS, OF ONE-THIRD TO EARL W. BELLINGER, OF WESTMORELAND, NEW YORK, AND ONE-THIRD TO GUY M. THOMAS, OF UTICA, NEW YORK.

FIRE ESCAPE.

Application filed October 22, 1924. Serial No. 745.141.

My present invention relates to fire escapes of the type wherein hinged members hinged to each other are provided with friction faces to engage a rope to control the descent of the person holding or supported upon the fire escape.

The purpose of my invention is to provide a fire escape of the class described which is simple and economical in construction, durable and efficient in use and easily applied to or removed from a rope or cable.

A further purpose is to provide a fire escape of the class described which can be easily applied to the rope in an obvious manner and applied broad-side to the rope, that is without having an end of the rope available but which fire escape will when mounted upon the rope have cross bars or links connecting the two members of the fire escape 20 together upon opposite sides of the rope.

Heretofore fire escapes of the general type here mentioned that have been attachable sidewise to the rope have had offset jaws or jaws projecting from one side of the hinged members. This construction is objectionable on account of the great strain that may be placed upon the device when used too energetically under the excitement of the stress of a fire. It is the purpose of this invention to overcome the disadvantage above mentioned by providing cross members or links which when the device is applied to the rope straddle the rope and so enable the fire escape to safely withstand the great strain it is subjected to.

Further objects and advantages of the invention will appear from the specification and claims herein.

Fig. 1 is a side elevation of a fire escape 40 embodying my invention with the main members separated to receive a rope.

Fig. 2 is a side elevation of the fire escape when the members are in closed position to grasp the rope.

Fig. 3 is a top view of the fire escape as shown in Fig. 2.

Fig. 4 is a top view of the fire escape with the parts in the position they occupy in Fig. 1.

Referring to the drawings in a more particular description it will be seen that the fire escape comprises two main members 5 and 6 permanently and pivotally connected by a cross bar 7 and detachably connected

by a second cross bar 8. In the drawings 55 the left hand member 5 is shown as remaining in the same position and the right hand member 6 is shown as the one which is swung upward to opened position, and this is the natural operation of the device, 60 although it will be obvious that in opening the members both may be swung part way from the vertical position.

The left hand member 5 is shown as comprising a strong piece of wood 9 which is 65 extended down far enough and shaped to form the handle 10 for this member. To the right hand edge of the piece of wood 9 is secured a strip of metal 11 which at its upper end is bent to the left in a curve 70 forming an eye 12 which closely encircles most of the length of the shank of a bolt 13 which bolt has its head 14 spaced forwardly from said eye 12 as particularly shown in 75 Figs. 3 and 4.

Immediately to the right of the strip of metal 11 and extending substantially the length thereof is placed and fixed the friction block 15 of this left hand member 5, 80 having in its right hand side as seen in Figs. 3 and 4 a semi-circular groove 16 adapted to engage one side of the fire escape rope 17. The block 15 and the metal strip 11 are securely fastened to the wood 9 of the member 5 by means of a bolt 37 piercing said 85 members near their top and by means of a screw 18 extending through the block and the metal strip near their lower ends and passing well into the wood 9.

Rigidly projecting to the right of the member 5 and at the rear side thereof as the parts are seen in Figs. 1 and 2 there is provided a cross piece 7. This is secured to the member 5 by said cross piece being pierced by the bolt 13 and held to said bolt 95 and against the eye 12 by the nut 20 on the rear end of said bolt. Said cross piece is further held from swinging relative to said member 5 through having a downwardly extending integral leg 21 the lower end of 100 which is securely fastened to the wood 9 of this member by means of a bolt 22 extending through said wood and the lower end of said leg. The member 21 is at the rear of the handle 9 as the device is shown in Figs. 1 and 2 but its length and width are indicated by the two spaced vertical dotted lines appearing on the handle 9 in Fig. 1. 105

This member 21 preferably has the same thickness as the cross piece 7 and with said cross piece 7 forms an integral inverted L-shaped part with the member 21 forming an anchor to help hold the cross piece 7 out at right angles to the general length of the handle 9.

The right hand main member 6 is preferably formed from a long strip of suitable metal bent or formed to provide an eye 23 to be mounted upon the outer end of the cross piece 7, a straight block-supporting portion 24, a handle 25 preferably formed by doubling said strip of metal into a long closed loop and an upwardly extending brace 26 spaced to the left of portion 24 as the parts are seen in Fig. 2.

The right hand member 6 is pivotally mounted upon the free end of the cross bar 7 by means of a bolt 27 which extends through a suitable hole in the free end of said cross bar 7 and then through the eye 23 of this member. The forward end of this bolt also extends through the second cross bar 8. This second cross bar 8 is held rigidly from swinging relative to said member 6 as by having its other end securely fastened as by rivet 28 to the brace 26 a short distance down from the upper or free end of said brace.

The upper end of said brace 26, that is the portion above the cross bar 8 forms a hook 29 projecting above the outer end of said second bar. The outer or free end of the cross bar 8 is offset outwardly as it approaches the brace 26 so that the hook 29 may lie in the plane next in front of the member 5 so that said hook may engage the left hand side of the shank of bolt 13 underneath the head 14, as the members approach closed position as plainly indicated in Figs. 2 and 3.

To the portion 24 of member 6 and upon the side thereof facing the other friction block 15 is securely fastened the friction block 30 for member 6 as by bolts 31. In its side towards the other friction block this friction block 30 has a semi-circular groove extending lengthwise of the block and adapted to engage one side of the fire escape rope or cable 17.

When it is desired to apply the fire escape to a rope the members 5 and 6 are swung apart to approximately the relative position shown in Fig. 1 and preferably as shown in said figure with the parts so arranged that the friction block 15 of the left hand member 5 is in alignment with and close to the rope 17 with the rope in front of the cross bar 7. When the members of the device are so separated it will be seen that the fire escape may be readily applied laterally or broad-side to the rope without having an end of the rope available. Then the handles of the device are

drawn towards each other bringing the opposite friction blocks 15 and 30 closely into frictional engagement with the rope on opposite sides of the rope. As the members of the fire escape are thus brought together it will be seen that the cross bar 8 with its hook 29 will cross in front of the rope and that as the members approach closed position the hook 29 will engage the projecting portion of the shank of bolt 13 underneath the head 14 and that thereupon the two members 5 and 6 will be pivotally connected to each other at their upper ends upon opposite sides of the rope. On account of this connection of the upper ends of both members on both sides of the rope the drawing together of the handles of the members to create sliding or holding friction upon the rope will produce no bending or distorting strain upon the hinging or co-operating parts of the fire escape. For this reason the device is well adapted to stand the great strain incident to its being used by inexperienced persons or by persons who under the excitement of a fire subject the device to greater strain than is necessary.

It will be noticed that the hook 29 is long enough to remain in engagement with the bolt 13 at any position to which the handles may be adjusted to get more or less friction upon the rope as may be needed under all the circumstances. After the descent upon the rope has been accomplished the fire escape is readily removed therefrom by simply opening the members to substantial right angles to each other whereupon the fire escape may be cleared from the rope.

It will be understood that the particular construction herein shown is simply illustrative of my invention and that modifications and changes may be made in the construction and shape of the parts without departing from the spirit of my invention as set forth in the claims herein. The loop formed by the bent strip of metal at the lower end of handle 25 affords a convenient place for the attachment of the usual straps or webbing, not shown, either direct to the handle or by means of a ring 32.

In order to enable a given size of fire escape to operate properly upon slightly varying sizes of cables and also to give a final adjustment in the device which will overcome any slight variations in the sizes or fit of the parts of the fire escape I make one of the friction blocks preferably friction block 30 adjustable relative to its member of the device. This is accomplished by having a set screw 33 screw-threaded into the block supporting portion 24 of the member 6 as particularly shown in Fig. 1 with the inner end of said set screw bearing against the adjacent surface of the friction block 30. It will be obvious that by

adjusting this set screw the block 30 may have its upper end positioned the slight desired distance from the portion 24. It will be understood of course that during such adjustment the nuts on bolts 31 are loosened sufficiently to allow the set screw to move the block and that after the block has been so adjusted the nuts on the said bolts are tightened to hold said block as near to the member 24 as the set screw 33 will allow.

What I claim as new and desire to secure by Letters Patent is:

1. In a fire escape the combination of two handled members having oppositely disposed friction faces adapted to engage a rope, a cross bar rigidly projecting from one member and permanently and pivotally connected to the other handled member adjacent said friction faces and to one side thereof, a headed lug projecting from the opposite side of said first handled member

and a second cross bar fixedly projecting from the second member past the other side of said friction faces and having a hook adapted to be brought into positive interlocking engagement with said headed lug when the members are closed, but leaving that side of the friction faces clear for the entrance of the rope when the members are separated.

2. In a fire escape the combination of two handled and pivotally connected members, oppositely disposed friction-faced blocks mounted on said members and adapted to engage a rope and means for adjusting one of said blocks relative to its member to vary the distance of its friction face from the other friction face.

In witness whereof I have affixed my signature, this first day of October, 1924.

GEORGE M. ROUSE.

CERTIFICATE OF CORRECTION.

Patent No. 1,626,698.

Granted May 3, 1927, to

GEORGE M. ROUSE.

It is hereby certified that the name of the second mentioned assignee in the above numbered patent was erroneously written and printed as "Guy M. Thomas", whereas said name should have been written and printed as "Guy G. Thomas", as shown by the records of assignments in this office; and that the said Letters Patent should be read with this correction therein that the same may conform to the record of the case in the Patent Office.

Signed and sealed this 1st day of November, A. D. 1927.

Seal.

M. J. Moore,
Acting Commissioner of Patents.
